J. R. WEAVER

ROPE GUIDE

Filed Aug. 10, 1922

Inventor

J. R. WEAVER,

Attorney

J. T. Darrow,

UNITED STATES PATENT OFFICE.

JOHN R. WEAVER, OF BALTIMORE, MARYLAND.

ROPE GUIDE.

Application filed August 10, 1922. Serial No. 580,850.

To all whom it may concern:

Be it known that JOHN R. WEAVER, citizen of the United States, residing at Baltimore city, and State of Maryland, has invented 5 certain new and useful Improvements in Rope Guides, of which the following is a specification.

This invention relates to a rope guide particularly designed to guide ropes on awnings.

Some of the objects of this invention is accordingly to provide an efficient rope guide that is very simple in construction and accordingly necessitates little expenditure 15 in its manufacture.

Other objects and certain advantages of this invention will appear from the more detailed description which appears below in connection with the appended drawing 20 which illustrates by way of example the preferred form of this invention and the device as it appears in use. In that drawing, Figure 1 represents the guide in operative position on an awning; Figure 2 is a perspective view of the guide and clamping plates about to be applied in position on the awning which is shown in section and perspective; and Figure 3 is a detail section of 25 the guide positioned on the fabric of the awning.

It will therefore be seen that fundamentally, the rope guide is provided with a surface exposed to the path of the rope which allows free and easy passage of the rope over that 30 surface although the latter is stationary.

In the preferred form of this invention as illustrated in the drawing, the rope guide presents a double curved surface 1 along which the rope 2 slides. To provide such a 35 surface, a strip of metal is preferably used having a semi-circular shape, the ends of the strip of metal forming prongs 3, 3 adapted

to be inserted through the material of the awning. The semi-circular portion of the strip is further provided with a transverse, 45 concave form, thus making a double curved surface, in its preferred form being a portion of a surface of a torus. The guide is thus simply provided with flanges 5, 5 which serve both as guides for the rope passing 50 through it and also as a support to hold the guide in position rigidly as will be set forth below. Associated with the guide proper as just described are clamping plates 6, 6 preferably two in number, having apertures 7, 7 55 adapted to receive the prongs of the guide.

In use, the guides, in number as many as are desired or necessary, are placed on the awning, with the clamping plates, the latter being positioned one above and one below 60 the fabric of the awning at the place or point where the guide is to be attached. The prongs of the guide are then passed through the clamping plates in the fabric and turned under as shown at 9, 9 thus clamping the 65 fabric of the awning between the clamping plates and holding the guide rigidly in place.

It is obvious that the shape or form of the guide may be varied widely without departing from the scope or spirit of this invention, and also that other means may readily be suggested to hold the guide in place on the awning.

I claim:—

In combination, a rope guide having a semi-circular member offering a toric surface to the path of movement of the rope, said semi-circular member ending in prongs, and clamping plates provided with apertures adapted to receive said prongs.

In testimony whereof he hereunto affixes his signature.

JOHN R. WEAVER.
